Ill., assignors to Da-Lite Screen Company, Inc.,
a corporation of Illinois

Application November 4, 1948, Serial No. 149,456

Term of patent 14 years

(Cl. D61—1)

To all whom it may concern:

Be it known that we, Hugo Bernzott and Curtis Talbot, citizens of the United States, residing at Niles and Chicago, in the county of Cook and State of Illinois, respectively, have invented a new, original, and ornamental Design for a Cap and Latch for Screen Holders, of which the following is a specification, reference being had to the accompanying drawing, forming part thereof.

Figure 1 is a perspective view of a cap and latch for screen holders, showing my new design.

Figs. 2, 3, 4 and 5 are top, side, bottom and rear end views respectively thereof.

We claim:

The ornamental design for a cap and latch for screen holders, as shown.

HUGO BERNZOTT.
CURTIS TALBOT.
